UNITED STATES PATENT OFFICE.

CHARLES O. MYERS, OF YORK SULPHUR SPRINGS, PENNSYLVANIA.

CAR-COUPING.

SPECIFICATION forming part of Letters Patent No. 310,535, dated January 6, 1885.

Application filed August 13, 1884. (No model.)

To all whom it may concern:

Be it known that I, CHARLES O. MYERS, a citizen of the United States, residing at York Sulphur Springs, in the county of Adams and State of Pennsylvania, have invented a new and useful Railroad-Car Coupler, of which the following is a specification.

In the accompanying drawings, to which similar letters of reference are made, indicating corresponding parts in the several figures, Figure 1 is a vertical sectional view of my invention. Fig. 2 is a horizontal sectional view of the same, and Fig. 3 is a cross-sectional view.

This invention has relation to means for coupling cars; and it consists in the construction and novel arrangement of devices, as hereinafter set forth, and pointed out in the appended claims.

In the accompanying drawings, the letter A designates the box or chair, which is attached to the car, and B is a movable draw-head within said box or chair, adapted to slide longitudinally. The draw-head B is provided with a flaring mouth, C, in front, and with lateral apertures E' in its rear portion, said apertures registering with lateral apertures or slots F' of the box A. In the top of the draw-head is made a slot near the bell-mouth for the passage of the front coupling-pin, F, which also passes through a perforation, b, of the box A. A similar slot, a', is made in the bottom of the draw-head below the slot a, and a perforation, b', in the bottom of the box registers therewith. When this front coupling-pin is in position, its relation to the box A is a fixed one, while the draw-head moves back and forth thereon for a short distance, which is regulated by the length of the slots a a'. The rear coupling-pin, W, is passed through perforations c and c', made, respectively, in the top and bottom of the draw-head, and the ends of this pin project sufficiently to engage a slot, d, made in the top of the box, and a similar slot in the bottom of the same. It will therefore be observed that this pin has a fixed relation to the draw-head, while it moves with said draw-head when the latter moves in the box A.

To the pin W is connected the rear end of the link D, which is permanently connected to this draw-head, the opposite draw-head being also provided with a similar link connected thereto in like manner. Each link D is formed with

a flat-pointed head, I, the edges of which are beveled, so that it will readily slide over or under the end of the link of the opposite draw-head in coupling. Each link has a pin slot or opening, e, in rear for connection with the rear pin, H, and is also provided with a front opening, g, and with an intermediate opening, h. When the draw-heads are coupled together, 55 each link is connected to its own draw-head and to the opposite draw-head by the front coupling-pin of the latter, so that if one pin should break the connections will be maintained by the other pins.

E indicates a transverse bar or bearing, which extends through the lateral slots E' and F' of the draw-head and its box A. To this bearing is connected a guide-rod, N, which extends to the rear through another transverse 60 bar or bearing, E', and through the transverse rear wall, S', of the draw-head and through the rear wall of the box A.

On the rod N and between the bearings E and E' is the spring S, and on said rod between the rear walls of the draw-head and box is the auxiliary spring S'. The rear spring operates to keep the draw-head from being injured by the shock of contact in coupling, and so, also, does the spring S; but this spring also 70 serves to allow the draw-head to be pulled outward somewhat, so that both front and rear coupling-pins will be brought to bear when the strain of the draft is on the links.

To the top of the box A is bolted or otherwise secured the spring-bar K, which is provided with upwardly-extending arms k, to which are pivoted the levers G, which are by their inner ends pivoted to the upper end of the front coupling-pin, F. These levers are 75 in oblique position when raised, extending upwardly and inwardly, and they are held in this position by the automatic action of the spring-arm to which they are pivoted. When so held, they support the pin in disengaged 80 position. When, however, the levers are operated to cause the pin to descend and engage the link, they take an oblique and downwardly-inclined position, in which they are automatically held by the elasticity of the spring-arms, so that the pin is held securely in its 85 engaged position.

The sliding draw-head herein described and the spring-operated pin-levers can be readily

affixed to some of the ordinary coupling-chairs now in common use.

Having described this invention, what I claim, and desire to secure by Letters Patent, 5 is—

1. The combination, with a coupler box or chair, of the sliding draw-head having its lateral walls slotted, the front and rear coupling-pins, the link, the bearing-plates extending 10 through the slotted walls of the box and draw-head, and the springs, substantially as specified.

2. The combination, with a coupler box or chair having lateral apertures, of a sliding draw-head therein, also having lateral apertures, the transverse bearings, the spring arranged between the said bearing-plates, and the spring between the rear wall of the draw-head and the rear bearing-plate, substantially 15 as specified.

3. The combination, with the sliding draw-head arranged within the box or chair, of the link having a front aperture for connection with the pin of the opposite draw-head, and a rear aperture and an intermediate aperture for connection with the front and rear pins of 20 its own draw-head, substantially as specified.

4. The combination, with a draw-head, of a coupling-pin, operating-levers pivoted thereto, and spring-arms, whereby said levers are automatically held in the raised or in the de- 25 pressed position, substantially as specified. 30

CHARLES O. MYERS.
